UNITED STATES PATENT OFFICE.

WILLIAM H. TAYLOR, OF FORT THOMAS, KENTUCKY, ASSIGNOR OF ONE-HALF TO THE
VAL DUTTENHOFER SONS COMPANY, OF CINCINNATI, OHIO, A CORPORATION OF
OHIO.

MANUFACTURE OF TURNED SHOES.

1,408,043.

Specification of Letters Patent. Patented Feb. 28, 1922.

Application filed May 25, 1921. Serial No. 472,515.

To all whom it may concern:

Be it known that I, WILLIAM H. TAYLOR, a citizen of the United States, and a resident of Fort Thomas, in the county of Campbell 5 and State of Kentucky, have invented certain new and useful Improvements in the Manufacture of Turned Shoes, of which the following is a full, clear, and exact description, reference being had to the accompanying drawings, forming part of this specification.

10 My improvements relate to the process of manufacturing turned shoes, whereby perfect lines and measurements may be obtained for the finished shoe without the difficulties now experienced and without the exercise of any unusual skill in the operator.

Heretofore in making turned shoes, the sole is first tacked to the last and the turned 15 upper also tacked in place and sewed to the sole leaving the counter portion open and not attached. Then the shoe is removed from the last, the upper turned right side out and the shoe again drawn on the last.

20 The shank piece is then inserted by lifting up the counter and the counter and shank piece are tacked to the heel portion of the sole and the upper accurately adjusted and formed on the last. The shoe is then removed and is ready for the heel. Inasmuch 25 as under this usual process the shank piece is inserted after the first lasting, allowance has to be made for the thickness of the shank piece when subsequently applied and 30 if proper allowance is not made when the shoe is turned, a fullness of the material at the instep will result, or, as more frequently happens, the shank will take more space than has been left, and the heel, instep and 35 waist-line measurements will not be accurately maintained for the finished shoe.

It is to avoid these difficulties that my 40 invention is directed and it consists in that certain novel method of operations to be 45 hereinafter particularly pointed out and claimed.

I have illustrated in the accompanying drawings, the turned shoe in the various steps of my improved process.

50 In the drawings,

Figure 1 is a perspective view of the last, showing the first steps in the process.

Figure 2 is a similar view with the sole applied to the last.

Figure 3 is a similar view with the turned 55 upper applied to the last.

Figure 4 is a similar view with the sewing of the turned upper completed.

Figure 5 is a perspective view of the shoe complete, except for the heel.

Figure 6 is a view of the complete shoe.

The first step in my new process consists in applying the shank piece 1 to the bottom of the last 2 in the position it is to occupy in the finished shoe where it is temporarily attached by pins or tacks from which the heads have been cut off. The sole 3 is then tacked in place on the last over the shank piece. The turned upper 4 is then drawn on the last and held temporarily by tacks 5 and the upper is then sewed to the sole by the line of stitches 6.

The shoe is then removed from the last, leaving the shank piece still on the last and the upper turned right side out. The shoe 75 is then lasted a second time, which brings the shank piece into proper position inside the shoe and the counter and upper are then tacked to the heel of the shank and the sole and the shoe is ready for the final operation of adding the heel 7 which is nailed on in the usual way. When the finished shoe is drawn from the last, the shank piece comes with the shoe, leaving the headless tacks in the last to be afterwards removed.

When the shoe is lasted the second time, the space required for the shank has been allowed for, so that the finished shoe has perfect lines and measurements. The heel, instep and waist-lines 9, 10, and 11 (Figure 90 5) which determine the fit of the shoe to the form of the last, will thus be absolutely accurate without the necessity of the operative making allowance for the shank and without the liability of the thickness of the 95 shank destroying or distorting the fine lines of the shoe.

Having thus described my invention, what I claim as new and desire to secure by Letters Patent, is:

1. The process of making turned shoes, which consists in first fitting and temporarily securing the shank piece to the bottom of the last and then lasting and sewing the turned upper to the sole with the shank 105 piece in position, then turning the shoe, relasting and finishing and removing the shank piece with the finished shoe.

2. The process of making turned shoes, which consists in first applying the shank piece to the last and securing the same temporarily, then applying the sole, then drawing the turned upper on the last and sewing it to the sole, then removing and turning the upper without removing the shank piece from the last, and then fitting the shoe to the last and securing the shank piece to the 10 counter, and then removing the shoe with the shank piece and attaching the heel.

3. The process of making turned shoes,

which consists in first applying the shank piece to the last and securing the same temporarily, then applying the sole, then drawing the turned upper on the last and sewing to the sole, then removing and turning the upper leaving the shank piece on the last, then relasting the turned shoe and securing the shank piece to the counter, and then finishing the shoe and removing the same from the last with the shank piece in place in the shoe.

WILLIAM H. TAYLOR.
